AUXILIARY FLUID SUPPLY VALVE

Clayton B. Pierce, New York, N. Y., assignor to
Emerol Manufacturing Co., New York, N. Y.,
a corporation of Illinois

Application July 11, 1945, Serial No. 604,460

2 Claims. (Cl. 137—153)

1

This invention relates to certain new and useful improvements in a valve for a system for supplying an auxiliary fluid to an internal combustion engine and is an improvement on the valve of the lubricating system disclosed in Patent No. 1,883,110 issued to Vernon W. Thompson and Burt N. Pierce, October 13, 1932.

The main object of my invention is to provide means for controlling the injection of a fluid to the manifold of an internal combustion engine to a nicety by the difference in pressure within the manifold and the atmospheric pressure whereby a movable wall is provided which is normally in engagement with a valve which meters the fluid injected into the cylinders of the engine.

Another object of my invention is to provide a supersensitive adjustment for the movable wall in respect to the valve whereby the movable wall can be adjusted to a nicety in order to control the injection of fluid.

A still further object of my invention is to provide a valve for a fluid injecting system which operates in a manner whereby control of fluid can be controlled properly irrespective of the viscosity of the fluid passing through the system.

A still further object of my invention is to provide in addition to the compound means for adjusting the movable wall additional means for limiting the movement of the movable wall in one direction.

A still further object of the invention is to provide a device so constructed that it can be adjusted for maximum feeding while idling.

With these objects in view:

Fig. 1 is a diagram illustrating one manner of applying my invention to an internal combustion engine.

Fig. 2 is a vertical section through the housing constituting the injector.

Fig. 3 is a diagram illustrating another form of injector showing it applied directly to the manifold of an internal combustion engine so as to be affected directly by the engine temperature, and

Fig. 4 is a vertical section through the form of device shown in Fig. 3.

In the embodiment of my invention as shown in Figs. 1 and 2 I have shown my injector applied to an internal combustion engine 1 having a manifold 2 to which is connected a charge forming device 3 of any of the well known constructions of carburetors now in use employing a throttle valve for controlling the supply of fuel mixture to the engine.

Arranged adjacent the engine is a tank 4 car-

2

ried by a support 5 said tank being adapted to contain a fluid of any kind which is to be fed to the engine in addition to the explosive charge. The particular kind of fluid used forms no part of my invention as I am aware that various kinds of fluids and liquids of all kinds can be used without departing from the spirit of my invention. The tank is preferably provided with a removable cover 6 and disposed on said cover is a housing 7 forming my injector for feeding auxiliary fluid to an internal combustion engine.

The housing 7 can be formed of any shape desired and has a pressure chamber 8 therein into which extends a conduit 9 having a strainer 10 which is disposed within the fluid tank. The pressure chamber is provided with an outlet conduit 11 which is connected to the intake manifold of the internal combustion engine and the conduits 9 and 11 form a conduit which is in communication with the fluid tank at one end and the manifold at the other so that in reality the housing is disposed in said conduit and as the housing contains a valve through which the fluid must pass the fluid is controlled by the different pressures, as will later be described. The conduit 9 has as a continuation a stem having an open upper end into which is removably secured a fitting having a valve seat 13. The lower end of the hollow tube 14 rests upon the fitting and surrounds the valve seat. The tube or sleeve 14 is provided with outlets 15 through which the fluid passes and is caught by a drip pan 16 which has a drip spout 17 disposed between a sight opening 18 formed in one of the walls of the housing, the glass forming the sight opening being secured against a gasket so as to form an air-tight joint. Surrounding the sleeve 14 is a coil spring 19 which carries at its upper end a cap 20 in which a valve 21 is disposed which cooperates with the valve seat 13 so that the passage of fluid will be controlled by the valve in respect to the seat.

The upper end of the housing is internally threaded into which is screwed a supporting sleeve B having an annular collar at its upper end which is milled so that it can be turned. Formed in the threaded portion is an annular groove the bottom wall of which is roughened and in which is disposed a packing 22 so that an air-tight joint is formed. This sleeve is also internally threaded into which is screwed an externally threaded sleeve 23 which also has an annular groove with a roughened bottom carrying a packing 24 to form an air-tight joint between the two sleeves.

By forming the groove rough the packing is prevented from turning as the two sleeves are turned to adjust them in respect to the housing. The threads of these two sleeves are of different pitch so that by adjusting the two independently the upper sleeve carrying the movable wall, as will later be described, can be adjusted to a nicety. The sleeve 23 is provided with a head 25 having a diaphragm chamber 26 formed by a cap 27 which is secured in position by turning the edge over as clearly shown at 28. Within the diaphragm chamber there is a diaphragm 29 secured therein over a packing so as to form an air-tight joint below the diaphragm and while I have shown a flexible diaphragm I wish it to be clearly understood that my invention is not limited to any particular kind of diaphragm as a movable wall could be used so as to be moved by the difference in pressure between the pressure within the housing and the atmospheric pressure. As the atmospheric pressure is usually constant and the pressure within the housing varies according to the vacuum in the manifold I am able by having this movable wall or diaphragm directly in contact with the head of the valve 21 to eliminate a lot of difficulties existing in prior types of valve actuated means through the medium of a movable wall which is in turn controlled by the various pressures.

In using the compound adjustment previously described formed by the two sleeves threaded one within the other with different pitch threads the position of the diaphragm which controls the position of the needle valve can be adjusted to a nicety so that the proper amount of fluid passing through the device can be controlled. In addition to the compound means I employ an adjusting screw 30 which works in a threaded bore formed in the cap 27 and is surrounded by a coil spring 31. This adjusting screw bears against or is in the path of travel of the movable wall so that the movement of the movable wall in one direction is controlled and as a thread of this screw has a pitch which differs from the pitch of the threads of the two sleeves forming the compound adjusting means I am able to further control and regulate the passage of fluid passing to the engine.

In order to prevent the upper sleeve from turning easily I provide a spring detent 32 which springs into a groove formed in the head to hold it in adjusted position and prevent it from turning with the supporting sleeve.

The housing 1 is provided with a vent passage-way 33 normally closed by a removable screw 34. This vent is used for adjusting, by operation of the adjusting screw 30, the amount of liquid feed at 75% engine load. The vent is opened, by removal of the screw, only while the engine is operating at idling speed. When the vent is opened, when the engine is at idle speed, the pressure in the device corresponds to that which would be present with the engine at 75% load. This arrangement permits the device to be properly adjusted while the engine is idling.

In the embodiment of my invention as illustrated in Figs. 3 and 4 I have shown my injector applied directly to the manifold 36 of an internal combustion engine 37 which is provided with a charge forming device having a throttle valve for controlling the supply of explosive charge to the engine. This causes the fluid injected into the cylinders of the engine to be affected directly by the engine temperature to maintain the fluid at a constant temperature, thereby maintaining uniform viscosity of the fluid whereby I am able to

maintain a uniform flow of fluid under all atmospheric conditions.

Disposed on a support 38 arranged adjacent the engine 37 is a tank 39 forming an auxiliary reservoir for the fluid to be injected into the engine. The tank is provided with a removable cover 40 through which passes a conduit 41 provided with a strainer 41' at its lower end within the tank 39 which may contain a fluid of any kind, the particular kind of fluid forming no part of my invention. The conduit 41 leads to the inlet 42 of a housing 43 forming my injector for feeding fluid directly into the manifold of the engine.

The housing is provided with a pressure chamber 44 having an outlet conduit in the form of a threaded nipple 45 screwed into a threaded bore formed in the engine manifold 36 forming with the conduit 41 a passageway from the auxiliary reservoir to the engine with the injector disposed so that the fluid passing therethrough is affected directly by the temperature of the engine to maintain the fluid at said engine temperature, thereby maintaining a substantially uniform viscosity of the fluid. This enables the amount of fluid fed to the engine to be substantially uniform and controlled to a nicety irrespective of the viscosity of the fluid within the tank.

The inlet 42 terminates in a stem into which is threaded a fitting 46 having a valve seat 47. The lower end of a tubular element 48 rests upon and is supported by a drip pan 50 which surrounds the valve seat 47 and is supported upon the end of the stem of the inlet 42. The tubular element 48 is provided with outlets 49 through which the fluid passes and is caught by the drip pan 50 which has a drip spout 51 disposed behind a sight opening 52 formed in one of the walls of the housing, the glass forming the sight opening being secured against a gasket so as to form an air-tight joint. Surrounding the sleeve 48 is a coil spring 53 which carries at its upper end a cap 54 in which a valve 55 is disposed which cooperates with the valve seat 47 so that the passage of fluid will be controlled by the valve in respect to the seat.

The upper end of the housing is internally threaded into which is screwed a supporting sleeve B having an annular collar at its upper end which is milled so that it can be turned. Formed in the threaded portion is an annular groove the bottom wall of which is roughened and in which is disposed a packing 56 so that an air-tight joint is formed. This sleeve is also internally threaded into which is screwed an externally threaded sleeve 57 which also has an annular groove with a roughened bottom carrying a packing 59 to form an air-tight joint between the two sleeves. By forming the groove rough the packing is prevented from turning therein as the two sleeves are turned to adjust them in respect to the housing. The threads of these two sleeves are of different pitch so that by adjusting the two independently the upper sleeve carrying the movable wall, as will later be described, can be adjusted to a nicety. The sleeve 57 is provided with a head 60 having a diaphragm chamber 61 formed by a cap 62 which is secured in position by turning the edge of the head over as clearly shown at 63. The diaphragm chamber has a diaphragm 64 secured therein over a packing so as to form an air-tight joint below the diaphragm.

In using the compound adjustment previously described formed by the two sleeves threaded one within the other with different pitch threads, the position of the diaphragm which controls the po-

sition of the needle valve can be adjusted to a nicety so that the proper amount of fluid passing through the device can be controlled. In addition to the compound means I employ an adjusting screw 65 which works in a threaded bore formed in the cap 62 and is surrounded by a coil spring 66. This adjusting screw bears against or is in the path of travel of the movable wall so that the movement of the movable wall in one direction is controlled and as a thread of this screw has a pitch which differs from the pitch of the threads of the two sleeves forming the compound adjusting means I am able to further control and regulate the passage of fluid passing to the engine.

The head 60 of the sleeve 57 is provided with a plurality of vertical grooves 67 like those shown in Figs. 7 and 2 into which extends a spring detent 68 carried by the housing to hold it from turning with the supporting sleeve.

The housing 43 is provided with a vent passageway 69 normally closed by a removable screw 70. The purpose of this vent is the same as previously described in respect to vent passageway 33.

In both forms herein shown to obtain the proper adjustment for controlling the flow of fluid to the engine, the pressure chamber is provided with a calibrated vent closed by a screw, which when removed when the engine is at idling speed causes a change of pressure in the pressure chamber to what it would be at 75% engine load. In other words, I have provided a method of obtaining and adjusting the amount of fluid feed that will occur at 75% engine load while the engine is idling.

Although the present device differs structurally from the system disclosed in the hereinbefore referred to United States Letters Patent No. 1,883,110 the principle of operation is the same. As the speed of the engine increases by the opening of the throttle the suction in the pressure chamber of the device is reduced and the flexible diaphragm is moved upwardly by the tension of the coil spring which is imparted to the diaphragm through the needle valve. Obviously the needle valve moves upwardly thus increasing the size of the passageway through the inlet valve into the pressure chamber with the result that a greater quantity of liquid will be drawn from the supply tank into the pressure chamber and flow therefrom to the intake manifold of the engine. As the speed of the engine decreases the suction in the pressure chamber is increased thus pulling the diaphragm downwardly and this in turn moves the needle valve downwardly against the tension of the coil spring. The downwardly movement of the needle valve reduces the size of the inlet opening at the inlet valve seat thus reducing the quantity of liquid drawn from the tank 4 and reducing the quantity of liquid fed from the pressure chamber to the intake manifold of the engine. The amount of liquid supplied by the device can be controlled to a nicety, as has previously been described, through rotary movement of the outer and inner sleeves in respect to one another thus adjusting the position of the diaphragm in respect to the valve seat.

I claim:

1. A pressure responsive device of the character described comprising, a housing, an open-ended outer sleeve threadedly mounted in one end of the housing for adjustment into and out of the housing, an open-ended inner sleeve threadedly mounted in the outer sleeve for rotary adjustment into and out of the outer sleeve, a flexible dia-

phragm carried by the inner sleeve intermediate the length thereof, a closure for the outer end of the inner sleeve, said diaphragm dividing the housing into two non-communicating chambers 5 one of which is a pressure chamber, the opposite end of the housing being provided with an inlet including a hollow stem disposed interiorly of the pressure chamber and having an open inner end provided with a valve seat, said stem being provided with an open-ended tubular extension having in its side wall an outlet passageway and communicating with the open upper end of the stem and with the pressure chamber, said stem extension serving as a guide for a needle valve 10 15 which is reciprocably mounted therein for co-operation with the valve seat of the stem, resilient means holding said stem in engagement with the diaphragm, and the pressure chamber being provided with an outlet.

2. A pressure responsive device of the character described comprising, a housing, an open-ended outer sleeve threadedly mounted in one end of the housing for rotatable adjustment into and out of the housing and provided externally of the 20 25 housing with means by which the sleeve may be rotated, an open-ended inner sleeve threadedly mounted in the outer sleeve for rotary adjustment into and out of the outer sleeve and provided externally of the housing with means by 30 35 which it may be rotated, means for holding the outer sleeve against rotation during rotation of the inner sleeve, a flexible plate-like diaphragm carried by the inner sleeve intermediate the length thereof, a closure for the outer end of the inner sleeve, said diaphragm dividing the housing into two non-communicating chambers one of which is a pressure chamber, the pressure chamber being provided with an inlet adapted for connection with a source of fluid supply, a hollow 40 45 stem in the pressure chamber constituting a continuation of said inlet and having an open upper end provided with a valve seat, a needle valve positioned between said valve seat and the diaphragm, an open-ended tubular element surrounding and constituting a guide for the valve and having an end supported on the inner end of the stem, a coil spring surrounding said guide and holding it in said position and engaging the valve and holding an end thereof in engagement 50 55 with the diaphragm, said valve guide being provided with a passageway providing communication between the interior of the guide and the pressure chamber, and the pressure chamber being provided with an outlet.

CLAYTON B. PIERCE.
